CARL H. ODER AND JAMES H. BAKER, OF FAIRFIELD, ILLINOIS.

SPARK-EXTINGUISHER.

1,119,448.

Specification of Letters Patent.

Patented Dec. 1, 1914.

Application filed March 30, 1914. Serial No. 828,271.

To all whom it may concern:

Be it known that we, CARL H. ODER and JAMES H. BAKER, citizens of the United States, residing at Fairfield, in the county of Wayne and State of Illinois, have invented certain new and useful Improvements in Spark-Extinguishers, of which the following is a full, clear, and exact description, reference being had to the accompanying drawings, forming a part hereof.

Our invention has relation to improvements in automatic spark extinguishers; and it consists in the novel details of construction more fully set forth in the specification and pointed out in the claims.

In the drawings, Figure 1 represents a side elevation of the extension-front of a locomotive boiler showing our invention applied thereto; Fig. 2 is an enlarged top plan and horizontal section on the line 2—2 of Fig. 1; Fig. 3 is a still further enlarged, side elevation of the device, parts being broken away; Fig. 4 is a top plan of the device at the point of connection thereof with the stack, a portion of the latter being indicated in cross-section; and Fig. 5 is a side elevation of a portion of a modified form of the device.

The present invention is particularly directed (though not restricted) to locomotive boilers, the object sought being to construct a device mounted in the engine stack which will automatically, and concurrently with the discharge of steam (exhaust or otherwise) into the stack, so moisten the cinders and sparks projected through the stack as to effectively and positively extinguish them, thereby rendering the same harmless and making impossible the starting of a fire should the sparks and cinders lodge on inflammable or combustible objects along the right of way of the railroad. The dampening of the cinders and sparks will likewise prevent injury and damage to crops, grass, forests and growing vegetables in the vicinity of railways.

The advantages of the invention will be fully apparent from a detailed description thereof which is as follows:

Referring to the drawings, and for the present to Figs. 1 to 4 inclusive, 1, represents the extension-front or smoke-box of a locomotive boiler, or that portion from which leads the smoke-stack 2. Into the front 1 is adapted to discharge the steam-

blower or nozzle 3 the jets being projected into the petticoat or lift-pipe 4 which directs the combustion products into the stack. These features are well understood in the art and require no further description. 60

In the present embodiment of our invention, we tap the boiler B below the water-line at a point adjacent the front 1, by means of a pipe 5, secured to the outer shell by brackets 6 or otherwise, and provided at a convenient point with a conventional cut-off valve V, the pipe leading along the side and over the top of the boiler, where it terminates in a vertical extension 5', secured to the main pipe by a conventional union 7. The pipe 5' discharges into a valve-casing 8 of conventional T-shape design, said casing being provided with a chamber a from which leads a discharge port or passage h normally closed by a valve 9, the stem 10 of which extends through one leg of the casing and through and beyond a stuffing-box 11 coupled to the casing, the outer terminal of the valve-stem 70 being connected to the adjacent outer terminal of a slide-frame 12 whose opposite terminal assumes the form of a rectangular sleeve or collar 12' sliding loosely over the pipe 13 leading from the port h of the valve casing. The end of the pipe 13 beyond the sleeve 12' is received or screwed into a central opening of a block 14 riveted to the outside of the stack 2, a second pipe 15 leading from the same block through the walls of the stack, and terminating in the stack in a 80 perforated spherical spray-head 16 secured to the pipe by an elbow 17 or equivalent manner. The width of the collar 12' is such as to overlap or project beyond, the sides 85 of the block 14 (Fig. 4) for a purpose presently to appear. 90

Pivoted to, and loosely embracing the sides of the block 14, and passing freely through slots or openings o in the stack walls, are the forked terminals 18, 18, of a 100 vertically oscillating tripping lever 19 disposed in the path of discharge from the nozzle 3 and lift-pipe 4, the free end of the lever being expanded so as to present ample surface to the jets of steam and gases impinging against its under surface. The fork members 18, 18, terminate in cam formations or lobes 20, 20, which bear against the portions of the collar 12' overlapping the block 14 (Figs. 3, 4,), and naturally with 110

an upward oscillation of the tripping lever (or valve-controlling lever 19) the collar 12' and hence the slide 12 of which it forms a part, will be pushed or moved outwardly 5 along the pipe 13. Normally, the collar 12' is held against the block 14 by the action of a compression spring 21 encircling the pipe 13, one end of the spring bearing against an abutment or nut 22 passed over 10 the pipe, by means of which the tension of the spring may be adjusted. The slide-frame 12 envelops the parts 13, 21, 8, 10 and 11, as shown, the frame being guided in its reciprocations by means of 15 pins or screws 21' projecting from the sides of the casing 8, and traversing the elongated slots 8 formed in the sides of the frame. The spring 21 normally holds the valve 9 to its seat by the pressure exerted 20 thereby against the collar 12' of the slide 12 coupled to the valve-stem 10, the length of the latter within the stuffing box 11 and the casing 8 being carefully adjusted by the nut n which secures the stem to the slide.

25 The operation will now be readily understood from the foregoing description and is substantially as follows: Assuming the normal position of the parts to be as indicated in Fig. 3, it is apparent that when the 30 throttle is opened and the engine starts to operate and exhaust through the nozzle 3 into the stack, the impact and pressure of the steam and gases against the bottom face of the lever 19 will force the lever upwardly 35 (see dotted position, Fig. 3), thereby causing the cams 20 to push on the collar 12' and force the slide 12 outwardly. This movement of the slide produces a pull on the valve-stem 10, thereby unseating the valve 9. If the valve V is open, water, under pressure of the steam in the boiler behind it, will be forced from the boiler through the pipes 5, 5', valve casing 8, pipes 13, 15, into and out of the spray-head 16, mingling in the 40 stack 2 in the form of a spray, with the hot and glowing cinders and sparks, and thus wetting and extinguishing the same. The lever 19 acts automatically under the impact of the steam and gases against it, and it only 45 requires the opening of the valve V to complete the operation. In the drawings, a conventional valve V is illustrated, but in practice it would be connected up in any suitable way known to the skilled mechanic, so that 50 the same could be operated from the cab of the engine. Such connections, however, are not here illustrated, because they are altogether too common to require description. When the exhaust of the engine is turned 55 60 into the atmosphere (after the fire is well under way) the lever 19 drops to its lowest position which is quite obvious from the drawing. In so doing, the spring 21 (which suffered compression with the lifting of the 65 lever) will force the collar 12' back against

the block 14 thereby pulling on the slide-frame 12 and pushing on the valve-stem 10 and seating the valve 9. The degree to which the valve may open can be determined and regulated by a proper adjustment of the 70 nut 22 which regulates the tension of the spring.

In some cases it may be desirable to supplement the action of the steam of the boiler which drives the water through the pipes to 75 toward the spray-head 16, by pneumatic pressure derived from compressed air or other gases. In that case the pipe 5 may be provided with a branch 25 below the water line α , leading to any suitable source of compressed air or gas supply. The pressure of such air or gas assists in driving the stream as it leaves the valve casing as quite obvious from Fig. 5 in which such a modification is shown. In this figure the parts illustrated 80 are identical with those already described 85 and are identified by the same reference numerals.

It is of course obvious that the device may be altered in many particulars, without in 90 any wise affecting the spirit of the invention; and we desire it to be understood that we do not wish to restrict ourselves to the details shown.

Having described our invention what we 95 claim is—

1. In combination with a locomotive smoke-box and stack thereof, a pipe leading from the water space of the boiler and terminating in a spray head in the stack, a valve-casing in the path of the pipe, a valve in the casing provided with a valve-stem passing out of the casing, a spring-controlled reciprocating slide member mounted on the pipe and coupled to the valve stem, a lever 105 hinged to the stack and oscillating in the stack in one direction under pressure of the gases flowing through the stack, and formations on the lever engaging the slide member for actuating the same and unseating the 110 valve with the oscillation of the lever by the gases as aforesaid.

2. In combination with a locomotive smoke box and stack thereof, a pipe leading from the water space of the boiler, a valve 115 casing for receiving the discharges from said pipe, a second pipe leading from the valve-casing through the wall of the stack, a spray-head in the stack forming the terminal of said second pipe, a port-controlling 120 valve in said casing, a stem leading from the valve through and out of the casing, a slide-frame mounted to reciprocate over said second pipe and terminating in a collar at the end adjacent the stack, a vertically oscillating lever in the stack, suitable formations at the axis of the lever engaging the collar aforesaid, a spring encircling the second pipe and having one end bearing against the 125 collar of the slide-frame, an adjusting nut on 130

the second pipe bearing against the opposite end of the spring and serving as an abutment therefor, and means for coupling the outer end of the valve-stem to the adjacent 5 end of the slide-frame, the parts operating substantially as, and for the purpose set forth.

In testimony whereof we affix our signatures, in presence of two witnesses.

CARL H. ODER.

JAMES H. BAKER.
